UNITED STATES PATENT OFFICE.

CHRISTIAN AALBORG, OF WILKINSBURG, PENNSYLVANIA, ASSIGNOR TO WESTINGHOUSE ELECTRIC AND MANUFACTURING COMPANY, A CORPORATION OF PENNSYLVANIA.

TROLLEY.

1,241,601.

Specification of Letters Patent.

Patented Oct. 2, 1917.

Application filed April 12, 1915. Serial No. 20,680.

To all whom it may concern:

Be it known that I, CHRISTIAN AALBORG, a citizen of the United States, and a resident of Wilkinsburg, in the county of Allegheny and State of Pennsylvania, have invented a new and useful Improvement in Trolleys, of which the following is a specification.

My invention relates to trolleys, and it has special reference to trolleys of the pantograph type that are adapted particularly to collect large amounts of current at high speeds.

One of the objects of my invention is to simplify and improve the construction and operation of pantograph trolleys and to provide a trolley that shall be inexpensive, light and durable in construction, effective and reliable in operation, and especially adapted to sensitively follow the irregularities of the trolley conductor with a rapidity of action that shall insure good electrical contact and smoothness of operation, even at high speeds.

Another object of my invention is to provide a trolley of the above indicated character which shall primarily be adapted for parallel movements in a vertical plane, which shall be yieldingly maintained in electrical contact with the trolley conductor by suitable elevating springs, and which, moreover, shall embody means for permitting of a slight drag or backward tilting movement of the pantograph frame, as a whole, under normal operating conditions and particularly when irregularities in the trolley conductor are encountered, the arrangement of parts being such as to tend to restore the pantograph frame to its initial central position.

Another object of my invention is to provide a simple, light and rugged supporting-frame structure which is carried upon a plurality of insulators, and upon which the pantograph frame and operating means are mounted in such manner as to minimize the frictional resistance usually imposed upon the rotatable parts of the device in the common form of pantograph trolley.

Another object of my invention is to provide an improved form of latch for restraining the pantograph frame in its lowered position and having a fluid-actuated release device in which a single coil spring is employed for performing the double function of opposing the working movement of the

piston and also for maintaining the latch in its locked position.

In the prior art, it has been customary to provide pantograph trolleys having merely vertical parallel movements, and to rely entirely upon the flexibility of the frame or that of the contact shoe to compensate for irregularities in the trolley conductor.

Moreover, the supporting bases of devices of this type have been relatively heavy and bulky in construction, while the fluid-actuated operating cylinders have been customarily supported upon, or suspended from, transverse operating shafts, thereby unnecessarily increasing the frictional resistance thereof. Furthermore, the pneumatically-released restraining latches have embodied a plurality of springs, one for reacting against the movable piston to return it to its initial position and the other for biasing the latch to the locked position.

According to my present invention, I propose to provide a device that shall, by reason of its improved construction, secure the benefits and advantages hereinbefore enumerated, and, at the same time, avoid the difficulties and disadvantages heretofore experienced in devices of this general character.

My invention is illustrated in the accompanying drawings in which Figure 1 is a view, partially in section and partially in side-elevation, of a pantograph trolley constructed in accordance with my invention, the trolley being shown in its upper position; Fig. 2 is a view, partially in side-elevation and partially in section, of the trolley in its lower or locked position; Fig. 3 is a similar view of a portion of the trolley in its upper operative tilted position; Fig. 4 is a plan view of a portion of the trolley shown in the foregoing figures; Figs. 5, 6, 7 and 8 are enlarged detail views of certain portions of the apparatus, and Fig. 9 is a fragmentary plan view of a modified form of my invention.

Referring to the drawings, the apparatus shown comprises a plurality of insulators 1, a supporting-frame structure 2, a current-collecting device 3, a pantograph frame 4, an interconnecting linkage 5, a plurality of elevating springs 6, a plurality of fluid-actuated operating cylinders 7 and a fluid-actuated latching device 8.

The supporting insulators 1 are located

in longitudinally disposed pairs on the respective sides of the apparatus and are severally provided with caps 10 having oppositely projecting lateral lugs 11 upon which pairs of longitudinally-disposed parallel supporting members 12 are mounted, the latter members preferably in the form of angle irons. Secured to the longitudinal supporting members 12, intermediate their ends, are a plurality of transversely disposed supporting members or angle irons 13 which, together with the members 12, constitute, in part, the frame-structure 2 upon which the pantograph frame 4 is mounted.

15 The pantograph frame 4 is of well-known construction and comprises a pair of jointed members 15 and 16, each of which embodies a pair of correspondingly located and like members 17 and 18 which are rigidly connected by cross-braces 19 and 20, in a suitable manner.

20 The members 17 and 18 are jointed or pivotally associated at 23, while the upper members 18 of the respective jointed frame members 15 and 16 are pivotally connected, at their upper ends, and suitably support the current-collecting device or contact shoe 3, which may be of any desired form for accomplishing the intended function.

25 30 The lower frame members 17 severally embody a main body member 25, to which rods 26 are attached and which comprises a toothed cam 27 and a downwardly projecting arm 28. Each member 25 is rigidly connected to one of the operating shafts 29 that are transversely disposed and are pivotally supported, at their respective ends, by means of bearing members 30 which are secured to the inner longitudinal supporting

35 40 angle irons 12. The lower extremities of the arms 28, that are associated with the members 17 on the same side of the device, are interconnected by means of the linkage 5.

45 Said interconnecting mechanism comprises a bell-crank lever 33, the respective ends of which are connected to the respective downwardly projecting arms 28 of the adjacent members 25 by means of pivotally connected links 34 and 35. Thus, the pantograph frame 4 is mechanically interconnected at its lower ends whereby an equalized parallel-motion device is provided which is capable of vertical movements only.

55 60 65 The bell-crank lever 33 is pivotally mounted upon a pin 38 carried by an intermediate pivotally mounted T-shaped member 39 which is disposed intermediate the springs 6 and the lower end 40 of which is pivotally mounted upon a shaft 41. The shaft 41 is carried by means of a bearing member 42 that is attached to the longitudinal supporting irons 12.

The several coil-springs 6 associated with each side of the apparatus are disposed in

substantial alinement, their inner ends being mechanically associated with end portions 44 of the T-shaped member 39 and their outer ends being attached to chains 45 which co-operatively engage the toothed cams 27 of the respective members 17.

70 The pivotal point 38 of the bell-crank lever 33 is located below the line of action of the springs 6, and intermediate said line of action and the pivotal point 41 upon which the member 39 is mounted. Thus, any force that is transmitted to the intermediate T-shaped member 39, through the agency of the interconnecting linkage 5, is delivered at a point outside of the center of pivotal movement thereof and, therefore, tends to actuate the member 39 in the one direction or the other about its pivot 41, for a purpose to be hereinafter set forth.

75 80 85 The several operating cylinders 7 are disposed in the central longitudinal plane of the apparatus, and are mounted or supported upon longitudinally located supporting members or angle irons 48 which are attached to the transverse supporting irons 13 and constitute parts of the framed supporting structure 2. A plurality of bearing members 49 are also secured to the supporting irons 48 for the purpose of guiding and supporting the transverse operating shafts 29 at their centers and, moreover, for taking up the thrusts of the operating devices 7 and maintaining the shafts 29 in alinement.

90 95 100 Each of the operating devices 7 comprises a cylinder 51 and a movable piston 52 contained therein which is suitably mechanically associated with one of the shafts 29 by means of a crank arm 54, the end of which is preferably provided with a roller 55 for engaging the piston 52. The crank arm 54 is pinned or otherwise fixedly attached to the shaft 29 and therefore serves to rotate said shaft when the piston 52 is actuated by the admission of operating-fluid to the cylinder 51, in any well-known manner. Thus, 105 the pantograph frame is lowered in position.

110 115 120 The fluid-released restraining latch 8, which is most clearly shown in Fig. 8, comprises a pivotally mounted latch 56 and a fluid-actuated device 57, both of which are associated with, and supported by, the central longitudinal supporting irons 48. The latch 56 is pivoted upon a pin 58 and is provided with an integral laterally projecting arm 59 that embodies a hook 60. The latch 56 is adapted to co-operate with a member or detent 61 that forms a part of one of the upper frame members 18 and is associated directly with the cross-braces 20. A member or rod 64, having an opening 65 in its lower end, co-operates with the hook 60 on the latch 56 and is surrounded by a coil spring 66, one end of which engages an enlarged flange 67 of the member 64 and the other end of which 130

rests upon a fixed plate 68 that is associated with the fluid-operating device 57. The spring 66, therefore, acts upon the member 64, and, through it, upon the latch 56 to 5 maintain said latch in its locked position.

The member 64 further constitutes a piston rod of the fluid-actuated device 57 and is adapted to be co-operatively engaged by a movable piston 69 that is carried within an 10 operating cylinder 70. The piston 69 may be of any desired form and is entirely separate and independent of the member or piston rod 64, by reason of which peculiar relation, the spring 66 serves in common to 15 act against the piston 69 during its working movement and to return it to its initial position and also to bias the latch 56 to its locked position.

Assuming the various parts of the trolley 20 to occupy the positions shown in Fig. 2, the pantograph frame may be raised by admitting operating fluid to the releasing device 57, whereby its piston 69 is forced downwardly against the spring 66 to cause the 25 latch 56 to be withdrawn from the detent 61. The several springs 6 upon the respective sides of the trolley are thereby permitted to act conjointly through the chains 45 and the toothed cams 25 to rotate the pivotally 30 mounted jointed frame members 15 and 16 in such manner as to tend to bring them together and thereby raise the current-collecting device or contact shoe 3 into engagement with a trolley conductor (not shown).

The interconnecting linkage 5 performs a 35 function of operatively connecting the several members 15 and 16 of the pantograph frame, insuring like movements thereof, and, moreover, constraining the pantograph 40 frame to vertical parallel movements. In the above description of the mode of operation of the apparatus, it is presupposed that the vehicle upon which the trolley is mounted is at rest, and the relative positions of the 45 various parts are indicated in full lines in Fig. 1, the pantograph frame being vertical and occupying its central and normal position.

Assuming that the vehicle is started into 50 operation toward the left, the frictional resistance of the sliding engagement of the current-collecting device 3 with the trolley conductor imposes a sufficient resisting force to cause the pantograph frame 4 to tilt or 55 drag slightly in a backward direction, as indicated in the dotted lines. This tilting movement is only permitted by reason of the association of the interconnecting linkage 5 with the pivotal T-shaped intermediate member 39, whereby said member is moved 60 slightly to the left above its pivotal point 41, as shown clearly in Fig. 3.

The pivotal movement of the member 39 is alone responsible for permitting the tilting 65 movement of the pantograph frame,

and, if the interconnecting linkage 5 were not associated with the members 17 of the pantograph frame in this way, said frame would be limited entirely to parallel vertical movements, and no tilting would be possible. 70

Moreover, as the T-shaped member 39 is moved to the left, as shown in Fig. 3, the tension of the left-hand spring 6 is somewhat relieved while that of the right-hand spring 6 is correspondingly increased and, 75 therefore, tends to restore the pantograph frame 4 to its central position, as will be understood.

Obviously, under running conditions, the drag of the pantograph frame 4, caused by 80 the frictional engagement of the contact shoe 3 with the trolley conductor, is balanced by the tension of the springs 6, and a position of substantial equilibrium is established. However, in the event that an irregularity 85 or deformation of the trolley conductor is encountered, it is evident that a much augmented resisting force is imposed upon the contact shoe 3. Hence, the pantograph frame 4 becomes tilted to a greater degree 90 in opposition to the springs 6 which, however, act to immediately and positively return the pantograph frame 4 to its balanced operating position. In this way, smooth operation and good electrical contact between 95 the current-collecting device and the trolley conductor is maintained at all times, even though severe irregularities are encountered at high speeds. The operation of the trolley is similar in all respects to that described 100 when the vehicle is running in the opposite direction.

Reference may now be had to the modification shown in Fig. 9, in which the body member 25 of the pantograph frame member 105 17 is freely mounted upon the end of the shaft 29 instead of being fixed thereto, as in the case of the apparatus shown in the preceding figures. Moreover, the body member 25 is provided with an integral projecting member 25^a which is adapted to engage, and to constitute a part of, a driving connection between the member 25 and the shaft 29, the latter being provided with a collar 110 29^a that is pinned or fixed thereto and embodies a projecting lug 29^b that is adapted for engagement with the arm 25^a.

Obviously, this driving connection is 115 effected only in one direction of rotation of the member 25 upon the shaft 29. For instance, when the springs 6 function to rotate the member 25 in a clockwise direction to effect the elevation of the pantograph frame 4, the rotational movement of the member 25 is transmitted to the shaft 29 through 120 the driving connection referred to. However, after the pantograph frame 4 has been raised into its normal operating condition, any slight downward movements during the 125 operation, by reason of the irregularities and 130

differences in height of the trolley conductor, are effected without rotational movement of the shaft 29. The body members 25, however, are rotated upon said shafts.

5 When it is desired to lower the trolley, the shaft 29 is turned in a counter-clockwise direction by the device 7. The lug 29^b engages the arm 25^a, and thereby actuates the pantograph frame to its lowermost position where

10 it is restrained by the latch 8.

In this manner, the up-and-down movements of the pantograph frame are not opposed in any way by the frictional resistance of the center bearing 49, except in the successive extreme uppermost positions assumed thereby, and, therefore, the operation of the trolley is sensitive, rapid and positive and accommodates itself readily to the operating conditions met in service.

15 20 Obviously, my invention is not restricted to the specific structural details and arrangement and location of parts herein set forth, as many modifications therein may be effected without departing from the spirit and 25 scope of my invention, and such modifications are intended to be covered in the appended claims.

I claim as my invention:

1. In a trolley, the combination with a 30 pantograph frame having widely separated supporting points, and a current-collecting device carried by said frame, of means disposed between said supporting points and operatively connected to said pantograph frame for elevating said frame and permitting tilting movements thereof.

2. In a trolley, the combination with a supporting structure, a pantograph frame mounted thereon at widely separate points, 40 and a current-collecting device carried by said frame, of means mounted between said points for elevating said frame, and means coöperating therewith for permitting tilting movements thereof.

45 3. In a trolley, the combination with a pantograph frame having a plurality of pivotally joined arms and a current-collecting device carried thereby, of resilient means disposed between said arms for elevating 50 said frame, and a mechanical linkage coöperating therewith for permitting tilting movements thereof.

4. In a trolley, the combination with a 55 pantograph frame having a plurality of arms and a current-collecting device carried thereby, of a plurality of coil springs disposed between said arms for raising the said frame in position, and mechanical means interposed between said springs and coöperating with said pantograph frame for permitting tilting movements thereof while biasing the frame to a predetermined position.

60 65 5. In a trolley, the combination with a supporting frame, a plurality of transverse

shafts, bearing members for supporting the ends of the shafts, a pantograph frame mounted on said shafts, and a current-collecting device carried by said frame, of a plurality of coil springs interposed between 70 said shafts and operatively connected to said frame for conjointly actuating it to its upper position, a pivotal member interposed between said springs and to which the adjacent ends of said springs are connected, and 75 means coöperating with said pantograph frame and said pivotal member for permitting tilting movements of said frame and for biasing said frame to its initial position.

6. In a trolley, the combination with a 80 supporting structure, a plurality of transverse shafts mounted on said structure, a pantograph frame mounted on said shafts, and a current-collecting device carried by 85 said frame, of a plurality of longitudinally disposed coil springs interposed between said shafts and acting conjointly to raise said frame, a pivotal member connected between said springs, and a linkage mechanism coöperating with said pantograph frame and with said pivotal member for permitting tilting movements of said frame and 90 concurrently moving said pivotal member to vary the tension of said springs.

7. In a trolley, the combination with a 95 supporting structure, and a pantograph frame comprising a pair of jointed frame members pivotally mounted thereon near their lower ends, of a pair of coil springs 100 conjointly acting to raise said pantograph frame, a member connected between said springs and pivotally mounted at a point out of the line of action thereof, a bell-crank lever fulcrumed intermediate its ends upon said pivotal member and at a point between the line of action of said springs and the pivotal point, and a plurality of links pivotally connected to the respective ends of said lever and to the corresponding lower ends of the respective jointed frame members.

110 8. In a trolley, the combination with a pantograph frame comprising a plurality of pivotally mounted jointed members and means interconnecting the lower ends of said members to form a parallel-motion mechanism, of a plurality of springs disposed between said members of said pantograph frame and conjointly acting to elevate said frame, and a movable member interposed between said springs and connected to said interconnecting means for permitting of tilting movements of said pantograph frame.

9. In a trolley, the combination with a supporting structure, and a pantograph frame comprising a pair of jointed frame 125 members pivotally mounted thereon at their lower ends, of a mechanical linkage interconnecting the lower ends thereof to constrain the movements of said pantograph frame to parallel motions, of a pivotally 130

mounted member upon which said interconnecting linkage is pivotally mounted, and a plurality of coil springs attached to said member and to the respective jointed frame members for elevating said pantograph frame.

10. In a trolley, the combination with a supporting structure, a pantograph frame comprising a pair of jointed frame members pivotally mounted thereon at their lower ends and a mechanical linkage interconnecting the lower ends thereof to constrain the movements of said pantograph frame to parallel motions, of means pivotally attached to said interconnecting linkage for elevating said pantograph frame and for permitting tilting movements thereof.

11. In a trolley, the combination with a supporting structure, a pantograph frame comprising a pair of jointed frame members pivotally mounted thereon at their lower ends, of a bell-crank lever pivotally mounted intermediate the lower ends of the respective jointed frame members, a plurality of links pivotally connected to the ends of said bell-crank lever and the respective lower ends of said jointed frame members, means for permitting tilting movements of said frame, and means for elevating said pantograph frame.

30 12. In a trolley, the combination with a supporting structure, and a pantograph frame, of a plurality of resilient means acting to raise said frame, a member pivotally mounted near one end thereof and disposed between said resilient means, a lever pivotally mounted between one end of said member and the point of mounting thereof, and means for operatively connecting the ends of said lever to the said frame.

40 13. In a trolley, the combination with a supporting structure, and a pantograph frame, of a member pivotally mounted on said structure, a lever pivotally mounted between one end of said member and the point of mounting thereof, and means for operatively connecting said lever to said frame.

14. In a trolley, the combination with a supporting structure, a plurality of rotatable transverse shafts carried thereby and a pantograph frame loosely mounted upon said shafts, resilient means tending to elevate said frame, and an operative connection between said shafts and said frame for rotating said shafts in one direction only, of fluid-actuated means carried by said supporting frame and operatively connected to said shafts for rotating said shafts in the opposite direction and lowering the pantograph frame.

50 15. In a trolley, the combination with a supporting structure, and a pantograph

frame, of a member pivotally mounted at one end, means for biasing said member to an upright position, a lever pivotally mounted between the ends of said member, and means for operatively connecting the ends 65 of said lever to said frame.

16. In a trolley, the combination with a supporting structure, a plurality of rotatably mounted shafts, a pantograph frame mounted upon said shafts, and a current-70 collecting device mounted upon said pantograph frame, of means disposed between said shafts and operatively connected to said frame for elevating said frame and for permitting a tilting movement thereof.

75 17. In a trolley structure, the combination with a supporting structure, and a plurality of rotatably mounted shafts, of a pantograph frame pivotally mounted on said shafts, and means for causing said shafts to 80 operatively engage said frame when turned in one direction.

18. In a trolley, the combination with a supporting structure, and a plurality of rotatably mounted shafts, of a pantograph 85 frame comprising a plurality of pivotally connected arms that are pivotally mounted on said shafts, means for causing said shafts to operatively engage said arms when turned in one direction, a plurality of springs 90 interposed between said arms and operatively engaging the same, a member pivotally mounted at one end thereof and disposed between said springs, a lever pivotally mounted on said member at a point between one end thereof and the point of mounting thereof, and means for operatively connecting the ends of said lever to said arms.

95 19. In a trolley, the combination with a 100 plurality of insulators, of caps for said insulators having outwardly extending arms, a plurality of longitudinal members rigidly attached to said arms, a plurality of lateral members rigidly attached to said longitudinal members, a plurality of lateral shafts rotatably mounted upon said longitudinal members, a jointed pantograph frame pivotally mounted on said shafts, means for turning said shafts in one direction, means 110 for causing said shafts to operatively engage said pantograph frame when turned in this direction, and means disposed between said shafts for permitting a tilting movement of said frame.

115 In testimony whereof, I have hereunto subscribed my name this 29th day of March, 1915.

CHRISTIAN AALBORG.
